UNITED STATES PATENT OFFICE.

WM. G. BUDLONG, OF HARTFORD, CONNECTICUT, ASSIGNOR TO HAMILTON W. CONKLIN AND JAMES W. CORNING, OF SAME PLACE.

CARPET-SWEEPER.

Specification of Letters Patent No. 24,176, dated May 24, 1859.

To all whom it may concern:

Be it known that I, WILLIAM G. BUDLONG, of the city and county of Hartford and State of Connecticut, have invented an Im-
proved Carpet-Sweeper, and do hereby de-
clare that the same is fully described and
represented in the following specification
and the accompanying drawings, of which—

Figure 1, is a top view; Fig. 2, an under
side view; Fig. 3, a transverse and central
section, and Fig. 4, a longitudinal section of
it. Fig. 5, is a transverse section taken
through one of the supporting levers of the
brush.

In such drawings A, exhibits the case of
the carpet sweeper while B, is a rotary brush
arranged therein and having its journals
a, a, extending through and supported by
two levers C, C, whose fulcra *n, n*, are ar-
ranged in the common axis of two driving
gears D, D, which are arranged respectively
at opposite ends of the frame or case A, and
so as to project a short distance out of the
bottom of the same as shown in the draw-
ings. The lower part of the case A, is pro-
vided with an opening *b*, (see Fig. 2,) through
which the rotary brush extends in
order that it may run in contact with the
carpet when the machine is placed on and
moved across the same. This rotary brush
has its bristles or bunches of bristles ar-
ranged around the body part *c*, in spiral or
helical rows as shown at *d, d*, the same being
to cause the brush to more thoroughly sweep
the carpet than would be the case were its
bunches of bristles to be arranged in circles
at right angles to the axis of the brush.
Furthermore each journal of the brush car-
ries a pinion *f*, which engages with one of
the driving gears D, D, so that when the
gears are put in rotation the brush will also
be put in revolution. The two levers C, C,
at their front ends are connected together by
a rod *g*, and each lever near its front end is
supported by an adjusting screw *h*, which
extends downward from the case A, and
screws through the lever or a projection
therefrom.

By means not only of the said levers ap-
plied to the brush and having their fulcra in
the common axis of the driving gears as de-

scribed but by the adjusting screws applied
to said levers the brush may be raised or
lowered relatively to the bottom of the case
A, and however it may be so adjusted its 55
pinions will be maintained in correct en-
gagement with the driving gears. Both in
front and in rear of the brush is a dust re-
ceiving drawer I, whose inner edge is fur-
nished with an inclined lip or guard *l*, which 60
projects therefrom and lays against the
brush as shown in the drawings. The pur-
pose of this lip being to prevent dirt or dust
from being thrown out of the drawer or es-
caping therefrom and between the drawer 65
and the brush during the movement of the
machine while it may be in use. The lip by
laying against the brush so that the latter
may work in contact with it presents so
broad a surface as will completely prevent 70
the escape of dirt from its drawer.

m, m, are small rollers or wheels for sup-
porting the machine on a carpet. In a car-
pet sweeper constructed as above described
we have a means not only of adjusting the 75
brush with respect to the carpet for the pur-
pose of causing such brush to sweep with a
proper degree of pressure thereon, but as
fast as the brush may wear, it may be low-
ered by its adjusting screws. Thus the 80
brush may be used until its bristles are en-
tirely worn up to the stock or body the pin-
ions of the brush under any such adjustment
being preserved in due relation or engage-
ment with the driving gears. The said car- 85
pet sweeper when moved over a floor, will
sweep it during each forward as well as each
backward movement of it thereon the dirt
taken up being alternately brushed into the
drawers.

I claim—

In combination with the gear wheel D,
and pinion *f*, at either end of the case, the
lever *c*, and screw *h*, by which the height of
the brush is adjusted and the pinion is en- 95
gaged with the driving gear, arranged sub-
stantially as and for the purpose specified.

WILLIAM G. BUDLONG.
